UNITED STATES PATENT OFFICE.

ALEXANDER HILL ANNAND, OF BUENOS AIRES, ARGENTINA.

ELECTROMAGNETIC RECORDING APPARATUS FOR TELEGRAPH-CIRCUITS.

1,150,326.

Specification of Letters Patent. Patented Aug. 17, 1915.

Application filed August 20, 1914. Serial No. 857,673.

To all whom it may concern:

Be it known that I, ALEXANDER HILL ANNAND, a subject of the King of Great Britain, and a resident of Buenos Aires, Argentina, have invented certain new and useful Improvements in Electromagnetic Recording Apparatus for Telegraph-Circuits; and I do hereby declare the following to be a full, clear, and exact description of the invention, such as will enable others skilled in the art to make and use the same.

The improvements provide for recording the elementary parts of the Morse code in a form such that the record may be either transcribed or it may be used to relay or repeat into a second circuit.

In recording signals a perforated medium, like a paper tape, is employed, and perforations are made by received reversed impulses of varying extent, or "blocks". This is clearly apparent when an ink recorder is employed, where a dot is on one side of a central base line, appearing as a truncated pyramid with obtuse angles, and a dash on the opposite side of the base line, a series of successive dots and dashes will be run together and a division between successive dots or dashes will be imperceptible, the group appearing as a "block". This is brought about by suitable adjustments of the transmitter at the transmitting end aided by the class of receiving relay, which in this case is Muirhead's gold wire relay. A group of dots or dashes has a characteristic extent and the number of individual dots or dashes in a "block" is easily translated by a skilled receiving operator; so that a block of given extent either on the dot or the dash side is readily translatable.

This improvement includes, as part of the recording combination, an electro-magnetic three-punch perforator at the receiving station, an automatic, motor-driven circuit breaker in local circuit with an electro-magnet operating the dot punch an automatic, motor-driven circuit breaker in a local circuit with an electro-magnet operating the dash punch, and a similar circuit breaker controlling a punch for the central line of feed holes; these circuit breakers are, respectively, and preferably, on motor-driven rotating shafts, the connection between the constantly-operating motor and the rotating shafts carrying the circuit breakers are, in each case, yielding or friction couplings, and there is a ratchet on each shaft which is

controlled by a pawl and electro-magnet. When the dot punch is to be operated, the main-line relay, through a local circuit, actuates an electro-magnet, withdraws a pawl and frees the shaft bearing the circuit breaker in the dot punch circuit; and when the dash punch is to be operated, a magnet in a similar manner frees the circuit breaker in the dash punch circuit.

Normally the circuit breakers in the dot and dash punch circuit are held at rest and the circuit breaker in the spacing hole circuit runs free; when the dot magnet is operated to release the dot circuit breaker the spacing circuit breaker is caught and held, and the same is true when the dash punch circuit breaker is used. The ratchets on the rotating shafts have ten teeth each, when the dot magnet punch, responsive to line impulse, releases the dot punch circuit breaker and the rotating shaft escapes one, two, three, or more teeth, according to the length of the line impulse, so that the letter H, composed of four dots, received in the block form, allows the shaft to escape four teeth and the circuit breaker on said shaft breaks the dot punch magnet circuit four times, thus punching four dots in the tape, and the dashes are similarly divided from received block impulses.

It has been demonstrated by me that the ten tooth ratchet wheel acts as a synchronizing device and any tendency to a deviation in speed of rotation between the transmitting agency, usually automatic, is rectified at the receiving station, the shaft being set back or advanced by the pawl striking the converging sides of adjacent teeth, so that no error exceeding five per cent. is encountered, and this is negligible in practical working.

The accompanying drawings illustrate the invention.

Figure 1 shows the essential elements of a three-key tape perforator and the relation of my improvement thereto. Fig. 2 shows the motor-driven shafts with yielding connections and details of the local means for operating either punch magnet. Fig. 3 is a top plan view of the perforator. Fig. 4 is a vertical front elevation in section, showing the magnets and circuit closing points in the perforator. Fig. 5 is a longitudinal cross-section showing the circuit closing contacts within the perforator. Fig. 6 is a detail of the ratchet wheel. Fig. 7 is a diagram

showing the rotating circuit breakers and the circuits connecting them to the perforator. Fig. 8 shows a manual transmitter and a modified form of receiving relay controlling the local circuit.

The relay employed is Muirhead's gold wire relay.

The cable *c* is in circuit with a polarized relay *r* having fixed contacts 11 and 12 and an armature or movable contact 10, arranged to maintain its position on either one side or the other until a variation in line condition changes its position. A condenser *d* is shown in the main circuit; this is usually placed between the cable and the receiving instrument. The three-key perforator is of the well-known Muirhead type, in which a finger-key, when depressed, initially sets a combination of elements for a dot and a feed hole, or a dash and a feed hole; the initial movement closes a local circuit through magnet 200 as soon as the combination is set by the movement of the finger key, and an arm 201, fixed to said magnet armature, operates the punch; the three punches are shown at 110, 111, and 112. Metal blocks 113 and 114, are vertically movable to mechanically connect the reciprocating end of the angular lever 201 with the selected punches. Retracting springs are shown at 115. The feed roll *g* has a circumferential line of pins entering the feed holes in tape *t*. A spring-pressed surface 120 has a finger contact 121 by which said surface may be withdrawn to allow the tape, when necessary, to be moved manually. The pivoted lever 201, as stated, gives final movement to the combination of punches as set by the depressed key; the pivoted lever 202, mechanically connected to the vertical reciprocating rod 116 sets the elements for the dot punch, and a similar lever 203, connecting with the vertical reciprocating rod 117, sets the elements for the dash punch. The levers 202 and 203 have retracting springs like 204. The levers 201, 202 and 203 are usually operated by three finger contacts, but for the purposes of my invention I have substituted for these finger keys electro-magnets 100 and 101; each magnet may have its core longitudinally perforated; a brass rod 102, carrying the armature 105, extends through said perforation into engagement with the dash key 203, and a brass rod 103, bearing armature 104, extends through the perforation of magnet 100 into engagement with the dot key 202. The lever 201 is operated by magnet 200 and an electric circuit to be described.

There is provided a series of motor-driven rotating circuit breakers arranged to divide a local circuit successively to transmit short impulses of current. These circuit-breakers are shown in Figs. 1, 2 and 7.

Referring to Fig. 2, there is a suitable

frame 90, in which are journaled three shafts 40, 41 and 42. The shaft 40 has fixed thereon a wheel 50 having its periphery divided into insulating and conducting spaces, and a spring finger 47 engages the periphery of said wheel. On shaft 41 is a similar wheel 51 engaging a similar contact finger 49, and on shaft 42 is a similar wheel 52 engaging with spring contact 48. These shafts 40, 41 and 42 have a constant tendency to revolve imparted to them by a shaft *s* driven by electric motor *m* in an electric supply circuit 64, containing a rheostat 63, by which the speed is maintained constant; shaft *s* has a toothed wheel *w*, meshing with a pinion *p* on shaft 66 journaled in frame 91; shaft 66 carries toothed wheel 60 meshing with wheel 62 on short shaft *n* and wheel 61 on short shaft *o*; friction clutches *f* connect shaft 66 with shaft 41, shaft *n* with shaft 40, and shaft *o* with shaft 42; there is thus imparted to the shafts 40, 41 and 42 a constant tendency to rotate. On the end of shaft 40 is toothed ratchet 89, on shaft 41 toothed ratchet 88, and on shaft 42 toothed ratchet 87; this ratchet wheel has ten teeth shaped substantially as shown in Fig. 6; a pawl 85 on lever 80, pivoted at 81, has chisel-shaped engaging terminals and reciprocates between the teeth of ratchet 88, on one side, and ratchet 89 on the other; a similar pawl 86 on lever 82, pivoted at 83, reciprocates between ratchets 88 on one side and 87 on the other; a brass plate 84 maintains the levers 80 and 82 in alignment. There are two electro-magnets 20 and 21, having armatures 18 and 19, respectively. A brass rod 22 is fixed to lever 80 and to armature 19, and has a bearing through which it reciprocates in the keeper 25 of magnet 21; a similar brass rod 23, fixed at one end to armature 18, and at the other to lever 82, reciprocates through the keeper 24 of magnet 20; armature 19 has a retracting spring 43 and adjusting spindle 45; armature 18 has a retracting spring 44 and a similar adjusting spindle 45; springs 43 and 44 are expansion springs and operate to press the armatures 18 and 19 away from the poles of the magnets, respectively. Pawls 85 and 86 are normally in engagement with ratchets 89 and 87 holding shafts 40 and 42 at rest, while shaft 41 is allowed to run free; when magnet 20 is energized, pawl 86 releases ratchet 87 and engages ratchet 88, shaft 41 is stopped and shaft 42 runs free; when magnet 21 is energized, pawl 85 releases ratchet 89 and holds ratchet 88, so that shaft 40 runs free and shaft 41 is held. Magnet 20 is in a local circuit with contacts 10, 11, of relay *r*; the local circuit includes battery 16 and wires 14 and 15. Magnet 21 is in circuit with contacts 10, 12, of relay *r*, including battery 16 and wires 13, 14. The rotating circuit breaker 48, 52, is in circuit 130

with magnet 101, including battery 206, the coil of magnet 101 and wire 171. The circuit breaker 50, 47, is in circuit with the coil of magnet 100, including battery 206, 5 the coil of 100 and wire 70; the return circuit in each case is through the ground *g* or the metal base of the apparatus; the circuit breaker 51, 49 is in circuit with the magnet 200, including battery 206, wire 71, 10 and the return circuit described.

The operation is as follows: Let us assume that a so-called "block" impulse is received and that the relay *r* closes its contacts 10, 12, and holds this contact during the continuation of the block impulse, and that this block impulse is equivalent in extent and due to the transmission of four dots, representing the letter *h*: magnet 21 attracts its armature 19, and withdraws pawl 85 from engagement with ratchet 89 into engagement with ratchet 88 and that circuit breaker 47, 20 50 makes and breaks circuit 70 and 206 four times, actuating magnet 100 four times in succession, and that lever 202 is depressed 25 four successive times, closing circuit through magnet 200 at either pair of contacts 250, 251, as shown in Figs. 4 and 5; this completes circuit through magnet 200, the lever 201 coating with the lever 202 each time 30 that lever 202 is depressed, from which it results that four dot perforations and four spacing perforations are made in the tape *t*. At the termination of the block impulse, the relay armature 10 takes an intermediate position, lever 80 is released, ratchet 88 is freed and ratchet 89 blocked, the parts are 35 in their normal position. Suppose that immediately following this a dash is transmitted by means of a reverse impulse, lever 10 40 engages contact 11 and a local circuit is completed through coil of magnet 20, battery 16, wires 14 and 15; magnet 20 attracts its armature 18, ratchet 87 is released and ratchet 88 is held; the circuit containing 45 coil of magnet 101 is closed via the elements 48, 52, 171, 101, 206 and return circuit *g*; this circuit is broken repeatedly by the circuit breaker 48, 52, during the time the relay holds the last described position, and as 50 many dash perforations are made at the opposite edge of the tape to that first described, together with corresponding center line feed perforations, as are equivalent to the duration of the block signal impulse received. Upon the cessation of the line impulse, the parts resume their normal position, ratchet 88 is free and the circuit breaker 49, 51, transmits a series of impulses in the local circuit 71, including the 55 coil of magnet 200, battery 206, wire 71, and the return circuit *g*, so that the line of feed perforations for the tape is continuous, due to the operation of the lever 201 actuated by the magnet 200.

60 It is to be understood that the rate of

automatic transmission and the rate of rotation of the shafts 40, 41, 42, bear a substantially fixed relation, and that synchronism is maintained, to the required degree of accuracy by employing a ten toothed 70 ratchet and an angular engaging pawl like 85 or 86, because a pawl, when engaging this ratchet, either accelerates or retards the movement of the shaft on which the ratchet is placed by engaging with the angular surface of a tooth, if it be out of unison. 75

In the drawings the perforator is shown with a metal base or frame, 205, and a bridge piece, 106, of brass, on posts supported upon the cross-bar, 207. The screw, 107, furnishes means for varying the extent of movement of rods 102 and 103. 80

In Fig. 8 I have shown a manual transmitter *v*, at station *i*, and a modified form of receiving relay *r* at station *j*. The operation is substantially like that already described. 85

The contacts 259 and 260 are registering contacts on the box cover and in the box containing the perforating mechanism; 90 these are useful in assembling the parts.

What I claim is:

1. The combination of a main circuit, a transmitting device and means for recording block impulses representing elemental Morse signals, said means including a tape perforator having a plurality of punches arranged in a line transverse to the line of tape movement, an operating magnet for each punch, local circuit connections for said magnets, a normally inactive automatic circuit breaker in the circuit of each punch magnet, a polarized controlling relay in said circuit, and means for operating either punch magnet by breaking its circuit successively for an interval determined by the actuation of said relay due to a block impulse. 100

2. The combination of a main circuit, a transmitter in said circuit and means for recording blocks of elemental Morse signals in perforated tape form, said means including an electro-magnetic perforator having a plurality of punches, electro-magnetic means for operating said punches, local circuit connections for said electro-magnetic means, a normally inactive automatic circuit breaker in the circuit of each punch, a polarized controlling relay in the transmitting circuit, and means for releasing either automatic circuit breaker to operate in its local circuit during the interval of actuation of said relay by impulses of varying duration. 110

3. The combination with an electro-magnetic tape perforator of a plurality of electro-magnets, one for each punch, an automatic, motor-driven circuit breaker for each magnet, a main-line electro-magnetic circuit controller, a main operating circuit for said controller, local circuit connections for each 120

punching magnet operated by said circuit controller, and means whereby said circuit controller releases a circuit breaker and operates a punch for and during each respectively different controller position.

4. The combination with an electro-magnetic tape perforator of a plurality of electro-magnets, one for each punch, an automatic motor-driven circuit breaker for each 10 punch magnet, an electro-magnetic circuit controller, an operating circuit for said controller, local circuit connections for each punching magnet, operated by said circuit controller, and means whereby said circuit 15 controller, responsive to impulses of respectively different duration in said operating circuit, releases one of the circuit breakers and operates one of the punch magnets, the determination of the punch magnet and the 20 duration of the operation of the local circuit breaker corresponding to the polarity and duration of the impulses in the controlling circuit.

5. The combination, in an electro-magnetic tape perforator, of a plurality of electro-magnets, one for each punch, an automatic motor-driven circuit breaker in the circuit of each punch magnet, local circuit connections for each punch magnet, a controlling 25 device for said local circuit, and means whereby said controlling device, when operated, releases a circuit breaker and operates a punch for and during each respectively different controller position.

35 6. The combination, in an electro-magnetic tape perforator, of a plurality of electro-magnets, one for each punch, an automatic circuit breaker for each magnet, local circuit connections for each punching magnet and circuit breaker, a local circuit controller and means whereby said circuit controller releases a circuit breaker to operate a punch magnet for respectively different intervals.

45 7. The combination, in an electro-magnetic tape perforator, of a plurality of electro-magnets, one for each punch; an automatic rotating circuit breaker for each magnet, a constantly operating motor, a motor-driven shaft for said circuit breaker, a friction coupling between said motor and shaft, a spur wheel on said shaft, a holding pawl 50

therefor, an electro-magnet controlling the position of said pawl, a main electro-magnetic circuit controller, a main operating 55 circuit for said controller, a local circuit including a punch magnet and said circuit breaker, and a local circuit including the pawl magnet and the contact points of said circuit controller.

8. The combination, in an electro-magnetic tape perforator, of a plurality of electro-magnets, one for each punch, an automatic rotating circuit breaker for each punch magnet, a plurality of motor-driven 65 shafts on which said circuit breakers are respectively fixed, a constantly operating motor, friction couplings respectively located between said motor and said shafts, a plurality of spur wheels, one for each 70 shaft, a holding pawl for each spur wheel, electro-magnets, one for each pawl, to control the engaging position, an electro-magnetic circuit controller, an operating circuit for said controller, a plurality of local 75 circuits each including a punch magnet and an automatic circuit breaker, and a plurality of local circuits each including a pawl magnet and contact points of said circuit controller.

9. The combination, of a transmitting circuit with means for recording blocks of elemental Morse signals, said means including a tape perforator having a plurality of punches, operating magnets, one for each 85 punch, an automatic rotating circuit breaker, a polarized controlling relay in said transmitting circuit, a constantly operating motor, a motor-driven shaft on which said rotating circuit breaker is fixed, a spur wheel 90 on said shaft, having ten acute angled teeth, a yielding coupling between the motor and said shaft, a holding pawl engaging the space between successive teeth of the spur wheel, an electro-magnet for controlling said 95 pawl, a local circuit including the contact points of the electro-magnetic circuit controller and said pawl magnet and a local circuit including a punch magnet and a rotating circuit breaker.
